(57) **CLAIM**

The ornamental design for a combined urea and fuel tank with frame, as shown, and described.

DESCRIPTION

FIG. 1 is an isometric view of a combined urea and fuel tank with frame, embodying a new design, viewed from above, in front of, and from the left side of the combined urea and fuel tank with frame;

FIG. 2 is an isometric view of the combined urea and fuel tank with frame of FIG. 1 viewed from above, in rear of, and from the right side of the combined urea and fuel tank with frame; FIG. 3 is a top plan view of the combined urea and fuel tank with frame of FIG. 1;

FIG. 4 is a right side elevation view of the combined urea and fuel tank with frame of FIG. 1;

FIG. 5 is a left side elevation view of the combined urea and fuel tank with frame of FIG. 1;

FIG. 6 is a front elevation view of the combined urea and fuel tank with frame of FIG. 1;

FIG. 7 is a rear elevation view of the combined urea and fuel tank with frame of FIG. 1;

FIG. 8 is an isometric view of a frame component of the combined urea and fuel tank with frame of FIG. 1, viewed from above, in front of, and from the left side of the tank component; and,

FIG. 9 is an isometric view of a tank component of the combined urea and fuel tank with frame of FIG. 1, viewed from above, in front of, and from the left side of the frame component.

The broken lines shown in the drawings are for illustrative purposes only and form no part of the claimed design.
